UNITED STATES PATENT OFFICE.

ARTHUR A. DOTY, OF ATTLEBORO, MASSACHUSETTS, ASSIGNOR TO PARKS BROS. & ROGERS, INC., OF PROVIDENCE, RHODE ISLAND, A CORPORATION OF RHODE ISLAND.

FLEXIBLE CHAIN.

Application filed July 28, 1927. Serial No. 208,992.

My invention relates to flexible chain fabrics, particularly adapted for use in articles of jewelry, such as bracelets, necklaces, pendants and the like.

5 An object of my invention is to provide a flexible chain fabric of simple construction, the parts of which may be readily stamped out of sheet metal which forms when assembled an extremely attractive flexible and strong type of fabric.

10 A further object of my invention is to provide, if desired, a fabric of this general type flexible, but when once arranged in desired position will tend to retain that set 15 position during use.

15 A further object of my invention is to provide a fabric of this description which may be readily constructed as to actually simulate a snake. The fabric of its own inherent construction resembles a snake to a certain degree, but to make it more resemble a snake, I may so ornament the outer visible surfaces thereof as to more closely simulate the markings on a snake and may 20 scallop the upper edges of each individual cup to make them more closely actually resemble snake scales.

25 A further object of my invention is to provide a chain fabric construction of strong 30 construction which may be easily and cheaply fabricated.

These and such other objects of my invention as may hereinafter appear will be best understood from a description of the 35 various embodiments thereof, such as are shown in the accompanying drawings.

In the drawings Fig. 1 is a side elevation of a portion of a chain fabric constructed in accordance with my invention.

40 Fig. 2 is a side elevation of the embodiment shown in Fig. 1 bent in use to show its flexibility.

45 Fig. 3 is a longitudinal sectional view of a chain constructed in accordance with my invention.

Fig. 4 is a disassembled perspective view of two stringed cups of the embodiment of my invention shown in Figs. 1 to 3, wherein the cup edges are circular.

50 Fig. 5 is a longitudinal sectional view of a portion of a modified form of a chain fabric wherein the string member comprises a small metallic chain.

55 Fig. 6 is a disassembled perspective view similar to Fig. 4 of a modified form of my

invention wherein each individual cup is made elliptical in shape.

Fig. 7 is a side elevation similar to Fig. 1 of the embodiment of my invention shown in Fig. 6, in which the nested cups are elliptical, having alternate cups of different colors to more closely imitate a snake with scalloped edges.

In the drawings, wherein like characters of reference generally indicate like parts throughout, 10 generally indicates a chain fabric constructed in accordance with the teachings of my invention. The fabric comprises a plurality of nested preferably metal cups 12 having lower ends 14 of smaller area than their upper ends 16, fitting into the cupped depressions 18 of adjacent cups and having the holes 20 through the lower ends 14 thereof. The cups are slightly flared so as to have straight side walls and a somewhat conical shape; as the result of this construction, the cups telescope readily, with the inside conical surface of one cup taking over the outside conical surface of the next cup, the coacting surfaces being in substantial parallelism. Therefore, one cup fits well into the next cup, and bears against it over an area which is annular in shape and of substantial width, thereby giving a strong, solid bracelet, heavy and firm to the touch and very durable in use.

While I preferably stamp the cup members 12 out of sheet metal, they may, if desired, be made in any desired fashion from metal or other suitable material. To arrange the cups 12 in the form of a continuous flexible chain, I string them on the string member 22 which extends through the holes 20 and is preferably secured under compression to the chain end cups 12 by the knots 24 or other means 24 thereon to retain said cups 12 together in flexible nested relationship.

Although I have shown the string member 22 as a preferable embodiment of means to retain said cup members 12 together under compression in flexible nested

115

preferably contacting relationship, other means for this purpose may be employed, if desired. The string member 22 is also preferably metallic and is flexible, so that the fabric may readily bend in use as shown in Fig. 2. A form of string member which I have found desirable to employ is the simple chain 22' shown in Fig. 5, in which case the means 24 to retain the cups together under

compression may comprise an extra link 24'.

In Figs. 3 and 4, I have shown a string member 22 of strong wire normally quite rigid in use, so that when the chain fabric 10 is bent, as for instance in use on a wrist bracelet the chain 10 will assume a more or less permanent rigid set position.

In the embodiment shown in Figs. 1 to 5, the individual cups 12 are shown circular. 10 If desired, however, these may be made of any desired shape such as the oblong cups 12', shown in Figs. 6 and 7. As the chain bends in use, it is apparent that the inside of the cups will freely flex over the contacting 15 outer surface of the inner ends of adjacent cups, so that the chain may readily flex to assume any desired position. If the cups 12 are made square, however, they will not flex quite so readily as the round and preferred 20 embodiment shown in Fig. 4, but if the sides of each cup are flared in the right degree and strung with the desired tension of the string member 22 to cause the desired compression on the cups, they may be so constructed as to function in use. Naturally, 25 however, the rounder the outer surface of the lower ends 14 of said cups, the more easily will the inner periphery of the cupped depressions of adjacent cups be able to slide 30 thereover to permit the chain to flex in use.

As stated, my invention from its own inherent construction simulates a snake in a certain degree. If desired, however, to more closely simulate a snake, the upper edges 35 26 of the upper ends 16 thereof may be escalloped as at 26, so that when assembled into the fabric 10 they may simulate snake scales. Also, if desired, the visible portions 13 of said cups may be additionally ornamented to simulate a snake by painting, 40 enamelling, mottling or otherwise, as for instance as shown in Fig. 7, by painting the alternate cups 12^a and 12^b of different colors to simulate snake stripes in use.

45 It is apparent that I have provided a flexible chain fabric adapted to a large variety of uses and particularly adapted for use as an ornamented fabric in articles of jewelry, simple in construction, easy and cheap 50 to manufacture, of pleasing and novel appearance and which may be more further ornamented to simulate a snake, fish or other flexible objects.

It is understood that my invention is not 55 limited to the specific embodiment shown and that various deviations may be made therefrom without departing from the spirit and scope of the appended claims.

What I claim as new and desire to secure 60 by Letters Patent is:

1. A flexible chain fabric consisting of a plurality of thin substantially conical cup members having rounded lower ends, and substantially straight side walls tapering 65 towards said rounded lower ends, the coact-

ing surfaces of successive cups being in substantial parallelism, whereby they engage each other over a substantial area, the cups being provided with holes in the lower ends thereof; and a retaining member flexible in all directions extending through said holes having the ends thereof secured to the end cups to retain said cups in flexible nested relationship and under compression, each cup having the hollow interior thereof deep enough to contain portions of adjacent cups telescoped within, whereby on free flexion of said fabric said side walls may obscure the lower ends of said cups and the fabric may be bent into a variety of different shapes and retain such shapes due to the compact nesting under compression of the cups. 70 75 80

2. A flexible snake simulating chain fabric consisting of a plurality of thin flaring substantially conical cup members with straight side walls, the edges of the cups being escalloped to simulate snake scales, and having rounded lower ends, the coacting surfaces of successive cups being in substantial parallelism, whereby they engage each other over a substantial area, the cups having holes in the lower ends thereof; and a retaining member flexible in all directions extending through said holes having the ends thereof secured to the chain end cups to retain said 85 90 95 cups in flexible nested relationship and under compression, each cup having the hollow interior thereof deep enough to contain portions of adjacent cups telescoped within, whereby on free flexion of said fabric said side walls may obscure the lower ends of said cups and the fabric may be bent into a variety of different shapes and retain such shapes due to the compact nesting under compression of the cups. 100 105

3. A flexible chain fabric consisting of a plurality of thin substantially conical cup members having rounded lower ends, and substantially straight side walls tapering towards said rounded lower ends, the coacting surfaces of successive cups being in substantial parallelism, whereby they engage each other over a substantial area, the cups being provided with holes in the lower ends thereof; and a freely flexible linked chain, readily bendable in every direction extending through said holes having the ends thereof secured to the end cups to retain said cups in flexible nested relationship and under compression, each cup having the hollow interior thereof deep enough to contain portions of adjacent cups telescoped within, whereby on free flexion of said fabric said side walls may obscure the lower ends of said cups and the fabric may be bent into a variety of different shapes and retain such shapes due to the compact nesting under compression of the cups. 110 115 120 125

In testimony whereof I affix my signature.
ARTHUR A. DOTY.
